UNITED STATES PATENT OFFICE.

THEODORE W. FOSTER, OF PROVIDENCE, RHODE ISLAND.

DESIGN FOR A BACK FOR BRUSHES.

SPECIFICATION forming part of Design No. 33,238, dated September 25, 1900.

Application filed August 24, 1900. Serial No. 27,955. Term of patent 7 years.

To all whom it may concern:

Be it known that I, THEODORE W. FOSTER, a citizen of the United States, residing at Providence, in the county of Providence and State of Rhode Island, have invented and produced a new and original Design for the Back of a Brush, of which the following is a specification, reference being had to the accompanying drawings, forming part thereof.

Figure 1 is a plan view of the back of a brush, showing my new design. Fig. 2 is a section of the back on the line X X of Fig. 1. Fig. 3 is a section of the handle on the line Y Y of Fig. 1.

As shown in the drawings, the leading and material feature of my design consists in the oval convex central panel of the back, terminating in the hexagonal form of the handle, ornamented by a border of raised foliated scrolls interspersed with floral ornaments inclosing the convex central panel, with a raised foliated scroll and floral ornament at the end of the handle. The flat upper side near the end of the handle is ornamented with a rose, the buds of which extend toward the brush-back, while the stem extends toward the end of the handle. The flat surfaces on each side of the central surface consist of raised foliated scrolls extending from each side of the stem of the rose along the two flat sides of the back of the handle. From the junction of the handle with the oval body of the back of the brush two foliated scrolls support a conventional rose ornament partly overlying the central convex panel. The foliated scroll on the left hand terminates in scrolled foliations

extending over the central surface and partly over the handle. These foliations are overlaid by the lower portion of the right-hand foliated scroll. On the right-hand side of 40 the central raised panel a bold raised and foliated scroll forms the ornamental border, while on the left hand a series of overlaid foliated scrolls form the border. On the upper end of the back a longitudinally-extending 45 bold foliated scroll, the foliations of which extend over the margin of the central convex panel, incloses a transversely-extending foliated scroll, the terminal foliations of which extend to and meet the foliated scrolls on 50 each side of the central convex panel. Floral ornaments are interspersed with foliations of the scroll. The whole presents to the eye the appearance of a boldly-ornamented border inclosing the central convex panel extending 55 to and over the hexagonal surfaces of the back of the handle, the edges of which merge with and extend into the ornamentation of the back and the end of the handle.

Having thus described my invention, what 60 I claim as new, and desire to secure by Letters Patent, is—

The design for the back of a brush substantially as herein shown and described.

In testimony whereof I have signed my 65 name to this specification in the presence of two subscribing witnesses.

THEODORE W. FOSTER.
